NEON TUBE OPERATING MECHANISM

Richard E. Davies, Williams, Ariz., assignor to Cleon Products, Inc., Phoenix, Ariz.

Application August 23, 1951, Serial No. 243,269

5 Claims. (Cl. 315—226)

This invention pertains to neon tube operating mechanism, and is particularly directed to improved apparatus for progressively illuminating and extinguishing a neon tube with novel operating mechanism which particularly protects the power transformer for the neon tube.

One of the objects of this invention is to provide an improved and simplified operating mechanism for progressively lighting and extinguishing a neon tube.

Still another object of this invention is to provide an improved control switch gear for progressively lighting and extinguishing a neon tube in which there are a minimum of operating parts and mechanical mechanisms utilized.

Still another object of this invention is to provide an improved operating control mechanism for a neon tube circuit which includes a shock tube or other device for maintaining at all times a minimum load on the secondary winding of the transformer for the neon tube.

Still another object of this invention is to provide an apparatus for progressively illuminating different lengths of a neon tube then extinguishing said tube either progressively or instantaneously while at the same time protecting the operation and efficiency of the power transformer for the neon tube.

Still another object of this invention is to provide a simplified and improved control apparatus for successively illuminating different portions of a neon tube to give the effect of a rise and fall of the light in the tube from zero to maximum and return.

Further features and advantages of this invention will appear from a detailed description of the drawings in which:

Fig. 1 is a plan view showing a neon tube operating mechanism incorporating the features of this invention.

Fig. 2 is a cross section on the line 2—2 of Fig. 1.

Fig. 3 is a fragmentary section on the line 3—3 of Fig. 1.

Fig. 4 is a fragmentary section on the line 4—4 of Fig. 1.

Fig. 5 is a fragmentary section on the line 5—5 of Fig. 1.

Fig. 6 is a fragmentary section on the line 6—6 of Fig. 1.

Fig. 7 is a fragmentary section on the line 7—7 of Fig. 1.

Fig. 8 is a fragmentary enlarged view of a portion of Fig. 1 showing the shock tube switch gear utilized in connection therewith.

As illustrative of an embodiment of this invention there is shown in Fig. 1 a neon tube operating mechanism comprising a main frame member 10 to which is fixed a series of insulated supports or pedestals 11 upon which are mounted the contact bars 12, 13, 14, 15, 16 and 17 each of which is connected through suitable leads 18, 19, 20, 21, 22 and 23 to the neon tube 24 to be controlled. Also mounted on the frame member 10 on suitable journal bearings 25, 26 and 27 carried on insulated supports 28 is the rotating operating shaft 29 which is connected through a suitable insulated coupling 30 to a drive motor 31 preferably mounted on the frame member 10.

Fixed in various rotary indexed positions on the shaft 29, as best seen in Figs. 3 through 7 inclusive, are a series of contacts arms 32, 33, 34, 35, 36, 37, 38, 39, 40 and 41 each terminating in their outer ends in arcuate

surfaces 42 which nicely slidingly contact or rotate in very close proximity to the edges 43 of the contact bars 12 through 17 inclusive.

The drive motor 31 is connected through suitable leads 44 to a suitable source of A. C. power supply such as the lines L1 and L2. The lines L1 and L2 are also connected to the primary winding 45 of a high potential transformer 46. The secondary winding 47 of the transformer 46 has one lead 48 connected to the contact bar 12, and its other lead 49 connected electrically through the journal bearing 25 directly to the rod 29 so that the contact arms 32 through 41 are electrically connected to the lead 49 to the secondary winding 47. With the motor 31 operating and the rod 29 rotating clockwise, in this particular example as indicated by the arrow 50, contact arm 33 rotates into position with its arcuate surface 42 coming in engagement or electrical contact with the bar 13 so as to then complete a circuit to energize the portion 51 of the neon tube 24 between the leads 18 and 19. Continued rotation of the shaft 29 by the motor 31 then brings contact arm 34 into engagement with contact bar 14 while contact arm 33 leaves contact bar 13 so that the neon tube is then lighted in both portions 51 and 52 between leads 18 and 20 and this procedure continues adding sections 53, 54 and finally section 55 or the completely illuminated tube from section 51 through 55 when contact arm 37 rotates into electrical contact position with the contact bar 17 at the top of the apparatus shown in Fig. 1. As contact arm 37 leaves its contact bar 43 contact arm 38 then electrically engages contact bars 16 to thus cut out the upper portion 55 of the neon tube and allow the remaining portion to continue to operate. The neon tube is then progressively extinguished through sections 54, 53 and 52 by progressive contact of the contact arms 39, 40 and 41 with their respective contact bars connected to the neon tube 24 as described.

As contact arm 41 leaves the contact bar 13 a final short-out arm 32 comes into electrical engagement with the bar 12 so as to provide a dead short across the secondary winding 47 of the transformer and thus provide a momentary complete extinguishment of the neon tube 24 after which continued rotation of the rod 29 by the motor 31 again repeats the cycle with contact arm 33 again contacting bar 13 and so on as described.

It is to be clearly noted that in this structure there are no moving mechanical parts other than the simple rotation of the shaft 29 with its contact arms rigidly fixed thereto which rotate by in close proximity to their respective contact bars so that actually there are no wearing or moving surfaces to ever get out of engagement or proper adjustment. Further, by utilizing this system there is no noise whatever involved except the normal rotation of the motor 31 which sound is insignificant so far as the proper adaptation and use of the device is concerned in any type of application. Thus there has been provided a highly efficient improved and simplified switching gear operating mechanism for progressively lighting and extinguishing a neon tube.

In Fig. 8 is shown a modified circuit for use in conjunction with the neon tube operating mechanism of Fig. 1 in which the contact arm 32 of Fig. 1 is mechanically connected as the arm 32a in Fig. 8 to be rotated by the shaft 29 but insulated therefrom by means of a suitable insulating bushing 56 which is drivingly secured to the shaft 29 and in turn rigidly supports the contact arm 32a. An annular contact ring 57 in electrical contact with the arm 32a and carried about the periphery of the insulating bushing 56, is engaged by a suitable contact brush 58, which brush in turn is connected through a lead 59 to a shock tube or other resistor means 60 which in turn is connected through a lead 61 to the lead 49 of the secondary winding 47 of the transformer 46. Thus rotation of the rod 29 and the contact arm 32a maintains electrical contact through the brush 58 and the lead 59 at all times with the shock tube or resistor 60. Thus, as the neon tube 24 is to be finally extinguished by final disconnection of contact arm 41 from the bar 13, contact arm 32a then engages contact bar 12 but in this case instead of creating a dead short across

the secondary winding 47 shock tube or resistor 60 is automatically cut in series with the circuit of the secondary winding 47 so as to maintain an appropriate load at all times on the secondary winding even when the tube 24 is completely de-energized. As the cycle again repeats as described contact 32a leaves contact bar 12 at the time the first section 51 of neon tube 24 is again placed in the circuit with the secondary winding 47 and the tube progressively lighted up to its top and then progressively cut off as described. It is to be understood, however, that rearrangement of the contact arms on the rod 29 can be such that the tube could be instantly completely de-energized after it was fully illuminated up to its top portion at which instant the tube or resistor member 60 would then be momentarily cut in until the progressive lighting up again was started as described.

Having thus fully set forth and described this invention what is claimed is:

1. In a neon tube operating mechanism, a frame member, a rod rotatably journaled in insulated supports on said frame, a drive means for rotating said rod, a plurality of axially spaced radially disposed contact arms fixed in electrical contact with said rotatable rod, a plurality of contact bars mounted on insulated support means on said frame and spaced axially of said rod in operative position with said contact arms on said rod, a neon tube having a plurality of terminals connected to a series of electrodes spaced along its length, and means for connecting each of said terminals to one of said contact bars, a potential transformer having a secondary winding, means permanently for connecting one lead from said secondary winding to one of said contact bars and to one end terminal of said neon tube, and means for connecting the other lead of said secondary winding to said rod, and means for supplying an electrical potential to said transformer and said drive means for said rod.

2. A neon tube operating mechanism comprising a frame, a rotatable rod journaled on said frame, a series of radially disposed contact arms fixed in axially spaced positions on and in electrical contact with said rod, a series of electrical contact bars mounted on said frame in electrical contactable relationship with said contact arms, a neon tube having a series of axially spaced terminals formed thereon, means for connecting one end terminal of said neon tube to one of said contact bars, and means for connecting the remaining of said terminals to the remaining contact bars, a high potential transformer, a secondary winding in said transformer, means for permanently connecting one lead from said secondary winding to the end terminal of said neon tube and to its connected bar, means for permanently connecting the other of said leads from said secondary winding to said rod and to a resistor, means for insulatively fixing the contact arm associated with the contact bar connected to said end terminal of said neon tube on said rod, means for continuously connecting the other end of said resistor to said insulated mounted contact arm, means for rotating said rod, and a source of power for energizing said means for rotating said rod and said transformer.

3. A neon tube operating mechanism including a neon tube having a plurality of axially spaced terminals each connected to a series of electrodes spaced along its length, a series of electrical contact bars one connected to each of said terminals, a series of movable electric contact arms operatively positioned relative to each of said bars,

a high potential transformer, a secondary winding in said transformer, means for permanently connecting one terminal of said secondary winding of said transformer to one of said contact bars and an end terminal of said neon tube, means for permanently connecting the other terminal of said secondary winding to all of said contact arms, and means for moving said arms relative to said contact bars.

4. A neon tube operating mechanism comprising a neon tube having a plurality of axially spaced terminals connected to a series of electrodes spaced along its length, a series of electrical contact bars one connected to each of said terminals, a series of movable electric contact arms operatively related to each of said bars, means for simultaneously moving all of said contact arms relative to said bars, means for connecting one end terminal of said neon tube to one terminal of a secondary winding of a high potential transformer, means for connecting the contact arm related to the contact bar connected to said end terminal of said neon tube connected to the one terminal of said secondary of said transformer to a resistor, means for connecting the other end of said resistor to the other terminal of the secondary winding of said transformer, means for connecting said other terminal of said secondary winding of said transformer continuously to all of the remaining contact arms, and means for connecting a source of alternating current power supply to said transformer and to the means for moving said contact arms.
5. In a neon sign operating mechanism comprising a frame, a rod rotatably journaled on said frame, a drive motor on said frame insulated from and coupled to drive said rod, a plurality of contact arms, means for insulatively mounting one of said contact arms in driven relationship on said rod, means for directly electrically connecting and drivingly mounting the remaining of said contact arms on said rod, a plurality of contact bars mounted on said frame in operative relationship to all of said contact arms, a neon tube having a plurality of terminals each connected respectively to a series of electrodes spaced axially thereon, means for connecting each of said terminals to one of said contact bars including an end terminal on said neon tube connected to the contact bar related to said insulatively mounted arm, a high potential transformer, a secondary winding in said transformer, means for connecting one end of said secondary winding to the contact bar associated with the insulated mounted contact arm on said rod, and means for connecting the other end of said secondary winding to said rod so as to be permanently electrically connected to all of the remaining contact arms, a resistor connected electrically to said rod, and means for connecting the other end of said resistor to said insulated mounted contact arm, and means for supplying an electrical potential to said transformer and said drive motor.
